UNITED STATES PATENT OFFICE.

CHARLES W. DUNHAM, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

ELECTRIC BELL.

1,117,484.

Specification of Letters Patent. Patented Nov. 17, 1914.

Application filed February 4, 1914. Serial No. 816,540.

To all whom it may concern:

Be it known that I, CHARLES W. DUNHAM, a citizen of the United States, residing at Swissvale, in the county of Allegheny and 5 State of Pennsylvania, have invented certain new and useful Improvements in Electric Bells, of which the following is a specification.

My invention relates to electric bells, and 10 particularly to bells of the type comprising a solenoid and plunger.

I will describe one form of bell embodying my invention, and then point out the novel features thereof in claims.

15 In the accompanying drawings, Figure 1 is a view showing in rear elevation, partly sectioned, one form of electric bell embodying my invention. Fig. 2 is a sectional view on the plane indicated by the line II--II in 20 Fig. 1.

Similar reference characters refer to similar parts in each of the views.

Referring first to Fig. 1, a gong 13 and an operating mechanism are mounted on a 25 casting 10, and are protected by a hood 21 which is pivotally mounted to swing on a screw 22 in the casting. The gong 13 is fixed to the casting 10 in a suitable manner (not shown), and the operating mechanism is 30 mounted on an inclined bed 12 forming part of the casting 10.

The bell operating mechanism comprises a solenoid 30, a plunger 19 which reciprocates in the solenoid, and a circuit controller 35 40 controlled by the plunger, all of which parts are carried by a bracket 17 which rests on the bed 12 and is secured thereto by screws 15.

The left-hand end (as viewed in Fig. 1) 40 of the bracket 17 is bent upwardly at substantially a right-angle to form a support 17^a. A second upright 17^b is formed on the bracket 17 by making two longitudinal slits extending into the bracket from the right-hand end (as viewed in Fig. 1) and by bending the middle or tongue portion upwardly at right angles. This leaves two side strips 17^c (only one of which is shown in Fig. 1); and these strips are bent upwardly as shown 50 in Fig. 1 to form a support for the circuit controller 40.

Mounted in suitable holes in the supports 17^a and 17^b is a tube 18 (preferably of brass) which supports the solenoid 30, and in which 55 the plunger 19 is mounted to reciprocate as

hereinafter explained. The left-hand end of the tube 18 is slightly spun over, and the rim thus formed is held firmly against the support 17^a by a plate 59 which latter is secured to the support 17^a by screws 39, by which construction the tube 18 is held firmly in place. The transverse sectional shape of the plunger tube 18 is as shown in Fig. 2, from which it will be seen that it is provided with three longitudinal race-ways 31, 32 and 33 in each of which are two balls 34. The downward movement of these balls is limited by stops 36 and 37, located in the race-ways and secured in place by rivets 51. An additional stop 35 is provided in each 70 race-way to prevent the upper balls from rolling out of place. The plunger 19 is cylindrical in form and is mounted to roll on the balls 34 so that it may reciprocate in the tube with practically no friction. The tube 75 18 is mounted substantially parallel to the bed 12, so that it is inclined between the horizontal and the vertical, the angle of inclination from the horizontal being preferably only slightly more than sufficient to 80 cause the plunger to roll downwardly due to the force of gravity when not acted upon by the solenoid.

By arranging the balls 34 in race-ways in the tube 18, it will be seen that when the 85 plunger is at rest, that is, in the lowest position of its stroke, the balls 34 are also at the lowest points of their travel, resting against the stops 36 and 37. Hence, in spite of any jarring which the bell may receive, 90 these balls remain in their proper position, and are ready to roll upwardly when the plunger is raised by the solenoid. By means of this construction, practically all danger of the plunger sticking is avoided. Furthermore, by locating the balls in race-ways in the tube 18 I am enabled to make the plunger circular in cross-section, so that the plunger rotates on its longitudinal axis and the wear on the plunger is thus distributed over 100 the entire surface, thereby prolonging the life of the bell.

The plunger 19 is provided with a tapper 20 which is adapted to strike the gong 13. As here shown, this tapper is in the form 105 of an enlarged head formed on the end of a stud 50 which is screwed into the end of the plunger. The reciprocation of the plunger 19 is limited in one direction by the engagement of the tapper 20 with the 110

gong and in the other direction by the engagement of the under side of the tapper head 20 with a diaphragm 38 of thin metal which is slightly bowed outwardly and is secured to the front plate 17^a by the screws 39. This diaphragm serves as a stop for the moving parts and also causes a slight rebound of the plunger and tapper as the latter reach their lowest position thereby causing a quicker and smoother action of the bell and also reducing slightly the energy required to operate the bell.

The circuit controller 40, which controls the circuit for the solenoid 30, may be of any suitable type, and forms no part of my invention. In the form here shown, it is similar to that shown in a co-pending application by Clinton O. Harrington, filed December 11, 1913, Serial No. 805,974, for circuit controllers. This circuit controller may be briefly described as follows: Mounted on the upturned ends of strips 17^c is a block 41 of insulating material provided with a hole in which is located a trough 61 of electro-conductive material. This trough carries a block 42 of electro-conductive material, preferably graphite, the upper surface of which is provided with a cylindrical recess as shown and described in the application by Harrington hereinbefore mentioned. Mounted to reciprocate in this recess is a hollow cylindrical member 43 of electro-conductive material, the curvature of which is substantially the same as that of the recess. This cylindrical member is clamped to a block 58 which is provided with a hole through which passes a stud 44 which is screwed into the lower end of plunger 19. This stud carries a collar 45 which cannot pass through the hole in block 58. When the plunger is raised by the solenoid from the position in which it is shown in Fig. 1, the collar 45 strikes the block 58 when the tapper 20 is about a quarter of an inch from the gong, so that during the remainder of the upward movement of the plunger the member 43 is moved to the left about a quarter of an inch. Then as the plunger returns, its lower end strikes the block 58 when about a quarter of an inch from the lowest point of

its stroke, thereby returning the member 43 to the initial position. Fixed to the block 41 is a spring 67 in which is journaled a roller 46, which roller is so located as to make contact with the cylindrical surface of member 43 when the latter is in the position in which it is shown in the drawing, but not when this member has been moved to the left by the plunger.

The member 43 and roller 46 are included in the circuit of the solenoid 30, and it is evident, therefore, that this circuit will be opened when the plunger reaches a point near the upper end of its stroke, and again closed when the plunger reaches a point near the lower end of its stroke.

The bell operating mechanism and the circuit controller are protected by a cover 49 which is attached to the bed 12 in any suitable manner.

I do not claim as my invention the circuit controller 40, this being the subject-matter of the hereinbefore mentioned co-pending application by Clinton O. Harrington, filed December 11, 1913, Serial No. 805,974, for circuit controllers.

Having thus described my invention, what I claim is:

1. An electric bell comprising a gong, a solenoid mounted with its longitudinal axis inclined between the vertical and the horizontal, longitudinal race-ways in said solenoid, balls adapted to roll in said race-ways, and a plunger adapted to roll on said balls and to strike the gong.

2. An electric bell comprising a gong, a solenoid mounted with its longitudinal axis inclined between the vertical and the horizontal, longitudinal race-ways in said solenoid, balls adapted to roll in said race-ways, stops fixed in said race-ways to limit the downward movement of the balls, and a plunger adapted to roll on said balls and to strike the gong.

In testimony whereof I affix my signature in presence of two witnesses.

CHARLES W. DUNHAM.
